UNITED STATES PATENT OFFICE

127,283

DESIGN FOR A COMBINED KEY CONTAINER AND COIN PURSE

Jacques Schwalbe, New York, N. Y.

Application August 14, 1940, Serial No. 94,417

Term of patent 7 years

To all whom it may concern:

Be it known that I, Jacques Schwalbe, a citizen of Belgium and residing at the city, county, and State of New York, have invented a new, original, and ornamental Design for a Combined Key Container and Coin Purse, of which the following is a specification, reference being had to the accompanying drawing, forming part thereof.

Fig. 2 is an end view;

Fig. 3 is a top view;

Fig. 4 is a rear elevation; and

Fig. 5 is a bottom view of a combined key container and coin purse, showing my new design.

I claim:

The ornamental design for a combined key container and coin purse, as shown.

JACQUES SCHWALBE.
